1967, Ser. No. 8,425

Term of patent 14 years

(Cl. D83—1)

FIGURE 1 is a perspective view of a holder for surgical instruments or similar article showing my new and ornamental design;

FIGURE 2 is a top plan view of the holder as seen in FIGURE 1;

FIGURE 3 is a bottom plan view of the holder as seen in FIGURE 1;

FIGURE 4 is a side elevational view of the holder as seen from the lower side of FIGURE 2;

FIGURE 5 is an end view of the holder as seen looking from the right of FIGURE 2 and rotated 90° clockwise; and

FIGURE 6 is a perspective view of the holder shown in FIGURE 1 with surgical instruments mounted thereon.

This is a continuation-in-part of design application Ser. No. D.4,057 filed Sept. 27, 1966 and now abandoned.

I claim:

The ornamental design for a holder for surgical instruments or similar article, substantially as shown and described.
